PIN RETAINING MEANS

Harry W. Stertzbach, John S. McPherson, and Arthur H. Filander, Columbus, Ohio, assignors to The Buckeye Steel Castings Company, Columbus, Ohio

Application June 18, 1931, Serial No. 545,324

10 Claims. (Cl. 213—72)

This invention relates to improvements in pin retaining means for use with vertical swivel yokes.

In vertical swivel yokes, the yoke is connected to the coupler shank by a vertical pin, which in some instances is notched for the reception of a horizontal key. One of the objects of the present invention is to provide a construction which will necessitate the correct positioning of the vertical pin, for otherwise, the retainer cannot be applied. The pin must be inserted right side up, and a slot portion of the pin must be in proper position to receive the horizontal key before the parts will function properly. Furthermore, the retainer is so constructed that after the horizontal key is in place, the pin cannot be removed until after the removal of the key.

A further object is to provide such a construction in which the retainer cooperates with a cotter pin or the like, which cotter is effective if the key is left out of the assembly either accidentally or intentionally.

With the foregoing objects outlined and with other objects in view which will appear as the description proceeds, the invention consists in the novel features hereinafter described in detail, illustrated in the accompanying drawings, and more particularly pointed out in the appended claims.

30 In the drawings,

Fig. 1 is a top plan view partly in horizontal section of a draft gear arrangement in which the vertical yoke and swivel coupler are connected by a vertical pin held in place by our improved retaining means.

Fig. 2 is a side elevation of the same with parts in longitudinal vertical section.

Fig. 3 is an enlarged vertical sectional view of a detail, and more clearly illustrating the means for retaining the swivel pin in place.

Fig. 4 is a front elevation of a portion of the same.

Fig. 5 is a bottom plan view.

Fig. 6 is a front view of a portion of a modification.

Fig. 7 is a longitudinal vertical sectional view of the same on the line 7—7 of Fig. 6.

Referring to the drawings, 1 designates a vertical swivel yoke or draft member, and 2 a coupler shank. These parts are connected by means of a vertical pin 3 of special construction, which provides what is commonly known as a swivel connection. A horizontal key 4 passes through these parts and is used to partially support the coupler and yoke assembly, and also as a safety

measure, for it provides draft means to the car sills 5 in case the yoke straps break.

The parts enumerated are assembled in the following manner: The yoke 1, with the customary draft gear and follower blocks, (not shown) in place between the straps, is raised into position between the center sills 5 and held in position by securing the usual carrier to the sills. The coupler shank is then inserted through the opening 7 in the striker 8, and the removable carrier iron 9 is then inserted in place. Then the pin 3 is inserted from below, as the cover plate 10 and the car body will not allow the pin to be inserted from above. The pin retainer 11 is put in position and the horizontal key 4 can then be inserted.

It will be noted in the above arrangement that the pin 3 is insertable from below, and is held in place by special retaining means which will now be explained in detail.

The vertical pin, in accordance with the present invention, can only be inserted in its correct position. Otherwise, the retainer 11 cannot be applied, that is, the pin 3 must be inserted right side up, and the notch portion 12 in the pin must be in its proper position to receive the horizontal key. The retainer 11, as best shown in Fig. 4, is of substantially inverted U-shape, and after the horizontal key 4 is in place, the retainer cannot be removed until after the removal of said key. The depending lugs 13 and 14 prevent such removal. The lug 13 is of such a depth that it will pass through the slots 15 of the depending bracket 16 when the pin 3 is elevated until stopped by the overhanging ledge 17 on top of the yoke, but also of sufficient depth so that when the key 4 is in place, the clearances between the various parts are not enough to permit the lug 13 to pass the bottom of the slot 15. When the notch 12 is not in position to receive the key 4, the lower cut-away portion 18 of the pin is not in position to receive the retainer 11.

The bracket 16 is provided with a rear wall 16a which extends for the full length of the bracket, and this construction allows the pin 3 to be wedged into transverse alignment by driving in the retainer 11 from one side or the other, providing of course, that the pin is not more than 90° out of alignment when the retainer is started through the slot 15.

A cotter pin 19 can be attached at the end of the key, but normally, when all parts are in position, the cotter is not necessary as part of the retaining means, for as explained above, the retainer 11 cannot be removed until after the key

4 is taken out. The cotter would be effective only if the key 4 is left out of the assembly, either accidentally or intentionally. Lugs 20 form part of the bracket 16, and one of them will extend over the cotter pin and prevent the retainer 11 and the cotter from raising. This reduces the shearing strain on the cotter, as any force tending to shear the cotter must be an upward force, and this force is resisted by the weight of the retainer 11 and key 3 in addition to the cotter.

The retainer is chamfered at 21 to assist in starting the pin by allowing it to be inserted at an angle. Of course, the retainer prevents the vertical pin from rotating.

Figs. 6 and 7 show a modified retainer 11a of substantially T-shape, which is shorter than the retainer 11, due to the use of one depending lug 13a at the center instead of two lugs at the ends. A cotter pin 19a is employed for securing the retainer to the bracket 16b. This modified construction is particularly useful when a deep center sill is used on the car and there is insufficient room between the sill and yoke bracket to start the longer retainer.

From the foregoing it is believed that the construction, operation and advantages of the invention may be readily understood by those skilled in the art, and it is apparent that changes may be made in the details disclosed, without departing from the spirit of the invention, as expressed in the claims.

What is claimed and desired to be secured by Letters Patent is:

1. In combination, a coupler shank, a draft member, a pivot pin connecting the coupler and member and having a notch at its lower end, integral means on the member engageable with the top of the pivot pin for limiting its upward movement, a bracket depending from the bottom of the member and provided with oppositely disposed slotted lugs, and a pin retainer extending through the slots of the lugs and having a side surface engageable with the notch of the pin for limiting downward movement of the pin and preventing the pin from turning, said retainer being prevented from removal from said slots so long as the pin is in its lowermost position, and said integral means being normally spaced from the head of the pin a sufficient distance to allow the pin to be elevated to a certain height to permit removal of the retainer from said slots.

2. In combination, a coupler shank, a draft member, a notched pivot pin connecting the coupler and draft member, integral means on the member engageable with the top of the pivot pin for limiting its upward movement, a bracket depending from the bottom of the member and provided with oppositely disposed slotted lugs, and a pin retainer extending through the slots of the lugs and having a side surface engageable with a notch of the pin for limiting downward movement of the pin and preventing turning of the latter, said pin being of cylindrical shape from end to end with the exception of its notched portion, said retainer being prevented from removal from said slots so long as the pin is in its lowermost position, and said integral means being normally spaced from the head of the pin a sufficient distance to allow the pin to be elevated to a certain height to permit removal of the retainer from said slots.

3. In combination, a coupler shank, a draft member, a notched pivot pin connecting the coupler and draft member, means on the member engageable with the top of the pivot pin for limiting

its upward movement, a bracket depending from the bottom of the member and provided with oppositely disposed slotted lugs, and a pin retainer extending through the slots of the lugs and having a side surface engageable with a notch of the pin for limiting downward movement of the pin, said retainer having a depending lug adapted to pass through one of the slots when the pin is in its uppermost position, said retainer being prevented from removal from said slots so long as the pin is in its lowermost position, and said first mentioned means being normally spaced from the head of the pin a sufficient distance to allow the pin to be elevated to a certain height to permit removal of the retainer from said slots.

4. In combination, a coupler shank, a draft member, a pivot pin connecting the coupler and member and having an upper key receiving notch and a lower pin retainer notch, stationary means on the member engageable with the top of the pivot pin for limiting its upward movement, a bracket depending from the bottom of the member and provided with oppositely disposed slotted lugs, a rigid rugged pin retainer extending through the slots of the lugs and having a side surface engageable with the lower notch of the pin for limiting turning and downward movement of the pin, and means for locking the retainer to said bracket, said retainer being prevented from removal from said slots so long as the pin is in its lowermost position, and said stationary means being normally spaced from the head of the pin a sufficient distance to allow the pin to be elevated to a certain height to permit removal of the retainer from said slots.

5. In combination, a coupler shank, a draft member, a pivot pin connecting the coupler and member and having an upper key receiving notch and a lower pin retainer notch, stationary means on the member engageable with the top of the pivot pin for limiting its upward movement, a bracket depending from the bottom of the member and provided with oppositely disposed slotted lugs, and a rigid rugged pin retainer extending through the slots of the lugs and having a side surface engageable with the lower notch of the pin for limiting turning and downward movement of the pin, said retainer being prevented from removal from said slots so long as the pin is in its lowermost position, and said stationary means being normally spaced from the head of the pin a sufficient distance to allow the pin to be elevated to a certain height to permit removal of the retainer from said slots.

6. The combination with a coupler member and a draft member, of a notched pin connecting said members, a bracket at the bottom of one of said members and having oppositely disposed slots, a removable retainer extending through said slots and engaging the notch of the pin for holding the pin in position, said retainer having a depending lug portion capable of passing through one of the slots when the pin is in a raised position, but cooperating with the bracket and acting to prevent removal of the retainer when the pin is in a lower position, and means on the upper portion of one of said members to limit the upward movement of the pin and to prevent the pin from being introduced into the members from above, said retainer being prevented from removal from said slots so long as the pin is in its lowermost position, and said last mentioned means being normally spaced from the head of the pin a sufficient distance to allow the pin to be elevated to a cer-

tain height to permit removal of the retainer from said slots.

7. The combination with a coupler member and a draft member, of a notched pin connecting said members, a key held in place by said members and extending through one notch of the pin, a bracket at the bottom of one of said members and having oppositely disposed slots, and a removable retainer extending through said slots and engaging the other one of the pin notches for holding the pin in position, said retainer having a depending lug portion capable of passing through one of the slots when the pin is in a raised position, but cooperating with the bracket and acting to prevent removal of the retainer when the pin is in a lower position, said key normally preventing the pin from moving upwardly to said raised position.

8. The combination with a coupler member and a draft member, of a vertical pivot pin connecting said members and provided with front and rear notches, a horizontal key held in place by said members and extending through the front notch of the pin, a bracket at the bottom of one of said members and having oppositely disposed slots, and a removable retainer extending through said slots and engaging the rear one of the pin notches for holding the pin in position, said retainer having a depending lug portion capable of passing through one of the slots when the pin is in a raised position, but cooperating with the bracket and acting to prevent removal of the retainer when the pin is in a lower position, said key normally preventing the pin from moving upwardly to said raised position.

9. The combination with a coupler member and a draft member, of a notched pin connecting said members, a key held in place by said members and extending through one notch of the pin, a bracket at the bottom of one of said members and having oppositely disposed slots, and a removable

retainer extending through said slots and engaging the other one of the pin notches for holding the pin in position, said retainer having a depending lug portion capable of passing through one of the slots when the pin is in a raised position, but cooperating with the bracket and acting to prevent removal of the retainer when the pin is in a lower position, said key normally preventing the pin from moving upwardly to said raised position, one of said members having means at its top to limit the upward movement of the pin and to prevent the pin from being inserted from above.

10. In combination, a coupler shank member, a draft member, a pivot pin connecting said members and having a notch in its lowermost end, integral means on one of said members engageable with the top of the pivot pin for limiting its upward movement, a bracket depending from the bottom of the member and provided with oppositely disposed slotted lugs, and a pin retainer extending through the slots of the lugs and having a side surface engageable with the notch of the pin for limiting downward movement of the pin and preventing the pin from turning, said pin retainer having depending lug means for preventing the retainer from being removed from the slots so long as the pin is in its lowermost position, said integral means being normally spaced from the head of the pin a distance approximately equal to the height of said depending lug means, so that the retainer and its depending lug means may pass through one of said slots when the pin is in its uppermost position, and removable means normally cooperating with said members and engaging the pin for preventing the pin from moving out of its lowermost position.
